UNITED STATES PATENT OFFICE.

CARL VÖLKNER, OF VIENNA, AUSTRIA-HUNGARY.

APPARATUS FOR MALTING.

SPECIFICATION forming part of Letters Patent No. 340,642, dated April 27, 1886.

Application filed September 23, 1885. Serial No. 177,948. (No model.) Patented in France July 13, 1885, No. 170,110; in Germany July 14, 1885, No. 34,114; in Belgium July 14, 1885, No. 69,589; in England July 17, 1885, No. 8,652, and in Austria-Hungary January 1, 1886, No. 25,853 and No. 67,386.

To all whom it may concern:

Be it known that I, CARL VÖLKNER, engineer, a subject of the Emperor of Austria-Hungary, residing at Vienna, in the Province of Lower Austria, in the Empire of Austria-Hungary, have invented certain new and useful Improvements in Malting Apparatus; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to that class of malting apparatus in which the process of malting is carried out pneumatically and by manual labor. This process consists in successively removing the steeped grain from one to the other of a series of malting tanks or bins having false perforated floors or bottoms and a chamber or space below said false bottom, and an imperforate bottom, said chamber or space being connected with an exhaust-duct, air previously cooled and charged with moisture being continuously drawn through the material and the chambers below the same into the exhaust duct or conduit, and carried out of the apparatus. In this class of apparatus access to the malting-tanks and the chambers below the malting-tanks cannot be had without great difficulty, therefore rendering the cleaning of the apparatus difficult and tedious.

The object of my invention is to provide means whereby easy and ready access may be had to each tank and its chamber below it, and whereby a series of malting-tanks may be arranged above one another, so as to occupy but a comparatively small space. This I attain by arranging the malting-tanks around a common air-exhaust shaft like a winding stairs, the grain being fed to the upper tank, and as the process of malting progresses is transferred from said tank to the next by the side and below said upper tank, and so on to the lowest tank, from which the malt is removed. The transfer of the material from one tank to the other is effected by hand, and

each transfer insures the turning of the charge. 5c The tanks have a perforated false bottom and an imperforate bottom, between which is formed a space or chamber that communicates by a valved port with the central air-exhaust shaft, thus requiring but one air-exhaust shaft 55 for all the tanks. The air drawn through the material is previously cooled and charged with moisture, and is admitted to the different malting floors and tanks from an air-shaft provided with valved air-inlets or slatted gates. 60

In the accompanying drawings, Figures 1 and 2 are sectional elevations of a malting-house embodying my invention, and Fig. 3 is a horizontal section of the same.

In the malt-house illustrated in the drawings I employ twenty malting-tanks, though a greater or less number may be employed, and these tanks T are arranged around a common air-shaft in the following manner, referring to Fig. 3, in which four of the tanks are shown: 70 The tank T¹ being the uppermost, that T² the next below and to one side thereof, the tank T³, below tank T² and adjacent thereto, and the tank T⁴, below and adjacent to tank T³, thus completing one convolution around the 75 central air-shaft, A, so that the tank T⁴ will come underneath tank T¹, that T⁵ under tank T², and so on throughout the length of the shaft A, said tanks T being arranged spirally around said shaft. 80

The tanks T are supported from a framework composed of four uprights, a, and eight uprights, a', to which are secured the brackets or other supports on which the tanks rest. The walls between and connecting the four inner uprights a form also the central air-exhaust shaft, A, and each tank has a false bottom, c, of perforated sheet metal or a reticulated or woven fabric and an imperforate bottom, d, between which false perforated bottom 85 and the imperforate bottom is formed a chamber or space that communicates with the air-shaft A through a valved port, b, so that the communication between said shaft and the chambers below the tanks may be cut off at any 90 time by manipulating the valve or damper stems or handles b', Fig. 1, that extend through the walls of the central shaft, A.

In Fig. 1 the tanks are shown in cross section, and the air previously purified, cooled, and moistened, as hereinafter described, is drawn through the material, the perforated bottoms *e* 5 of the tanks *T*, the chambers below the same, and the valved ports *b* into the air-shaft *A* by an exhaust-fan, *c*, and discharged into the atmosphere.

The air admitted to the malting-tanks is 10 taken from without and passes through a purifying and cooling tower or shaft, *f*, and is charged with moisture during its passage through said shaft, as follows: Adjacent to the vertical shaft *f* are two shafts, *k* and *k'*, of the 15 same height as said shaft *f*. The air from without passes through shaft or duct *k*, either entering at top or bottom, as may be desired, or according to the temperature or degree of pollution of the air. From shaft or duct *k* the 20 air enters the shaft *f* at its lower end, and within the shaft are arranged a series of perforated partitions, that extend alternately from one of the walls of the shaft to near the opposite wall thereof, thus forming a zigzag passage for the 25 air, a portion of which also passes through the perforated partitions. At the upper end of the shaft *f* is located a spraying apparatus, *l*, consisting of perforated pipes, or pipes provided with rose-heads, to which water is fed 30 from a reservoir, *h*. Said water falling through the successive perforated partitions in the form of spray, serves to cool and purify the air and charge the same with moisture. From the shaft *f* the air passes into shaft *k'* at its upper 35 end, and is distributed to the different malting floors and tanks through valved ports *g*, or ports provided with slatted gates *g*, so that the volume of air admitted to each malting floor or tank may be regulated or cut off at 40 will, or according to the state of the material in the tanks.

Above the upper tank are located the steep-

ing-tanks *i i*, in which the grain is steeped before being charged into the upper malting-tank.

Having now described the nature of my said 45 invention and in what manner the same is to be performed, what I claim, and desire to secure by Letters Patent, is—

1. In a malting-house, the combination, with 50 a single vertical air-shaft, of a series of malting tanks or floors arranged spirally around said air-shaft and having a space below their perforate false bottom, in communication with the air-shaft through suitable valved ports, substantially as and for the purpose specified. 55

2. In a malting-house, the combination, with 60 a single vertical air-exhaust shaft and an air-exhausting apparatus connected with said shaft at the bottom thereof, of a series of malting tanks or floors arranged spirally around 65 said air-shaft and having a space below their perforate false bottoms communicating with the air-shaft through valved ports, substantially as and for the purpose specified.

3. In a malting-house, the combination, with 70 a single air-exhaust shaft, an air-exhausting apparatus connected therewith at its lower end, and a series of malting tanks or floors arranged spirally around the air-exhaust shaft having spaces below their perforate bottoms 75 in communication with said shaft through suitable valved ports, of an air-supply shaft in communication with the malting tanks or floors through suitable valved ports, and means for cooling and for purifying the air admitted and charging the same with moisture, substantially as and for the purpose specified. 75

In testimony whereof I affix my signature in presence of two witnesses.

CARL VÖLKNER.
